US00D870567S

(12) **United States Design Patent** (10) **Patent No.:** **US D870,567 S**
Jacober et al. (45) **Date of Patent:** **** Dec. 24, 2019**

(54) **CONTOURED NECK FOR A BEVERAGE CONTAINER**

(71) Applicant: **Ball Corporation**, Broomfield, CO (US)

(72) Inventors: **Mark A. Jacober**, Arvada, CO (US); **Howard C. Chasteen**, New Port Richey, FL (US)

(73) Assignee: **Ball Corporation**, Broomfield, CO (US)

(**) Term: **15 Years**

(21) Appl. No.: **29/603,543**

(22) Filed: **May 10, 2017**

Related U.S. Application Data

(62) Division of application No. 29/430,744, filed on Aug. 29, 2012, now Pat. No. Des. 787,952.

(57) **CLAIM**

The ornamental design for a contoured neck for a beverage container, as shown and described.

DESCRIPTION

FIG. 1 is a front perspective view of a contoured neck for a beverage container;

FIG. 2 is a top plan view thereof; and,

FIG. 3 is a front elevation view thereof.

The broken lines showing environment are for illustrative purposes only and form no part of the claimed design.

1 Claim, 2 Drawing Sheets
